UNITED STATES PATENT OFFICE.

RALPH R. SCHEIBE, OF CAMBRIDGE, MASSACHUSETTS.

DESIGN FOR A BOUDOIR-TRAY.

52,678.

Specification for Design.

Patented Nov. 12, 1918.

Application filed February 5, 1918. Serial No. 215,544. Term of patent 3½ years.

To all whom it may concern:

Be it known that I, RALPH R. SCHEIBE, a citizen of the United States, residing at Cambridge, in the county of Middlesex and Commonwealth of Massachusetts, have invented a new, original, and ornamental Design for a Boudoir-Tray, of which the following is a specification, reference being had to the accompanying drawing, forming a part thereof.

The accompanying drawing is a perspective view of a boudoir tray showing the new design.

I claim:

The ornamental design for a boudoir tray substantially as shown, or any colorable imitation thereof.

RALPH R. SCHEIBE.
